DESIGN FOR A PORTABLE GLASS WASHER

Emanuel Nielsen and Edward R. Mross, Racine,
Wis., and Vincent W. Cunningham, Chicago, Ill.; said Nielsen and said Mross assignors to said Cunningham

Application October 26, 1939; Serial No. 87,872

Term of patent 14 years

To all whom it may concern:

Be it known that we, Emanuel Nielsen and Edward R. Mross, citizens of the United States, residing at Racine, in the county of Racine and State of Wisconsin, and Vincent W. Cunningham, a citizen of the United States, residing at Chicago, in the county of Cook and State of Illinois, have invented a new, original, and ornamental Design for a Portable Glass Washer, of which the following is a specification, reference being had to the accompanying drawing, forming part thereof.

In the drawing the figure is a perspective view of a portable glass washer showing our new design.

The other side of the portable glass washer is substantially the same as the side shown in the drawing.

We claim:

The ornamental design for a portable glass washer, substantially as shown and described.

EMANUEL NIELSEN.
EDWARD R. MROSS.
VINCENT W. CUNNINGHAM.
